UNITED STATES PATENT OFFICE.

BUELL FRANK NEWCOMB, OF WATKINS, NEW YORK, ASSIGNOR OF ONE-HALF TO CLAY M. NEWCOMB, OF SAME PLACE.

FENCE.

SPECIFICATION forming part of Letters Patent No. 390,186, dated September 25, 1889.

Application filed December 8, 1887. Serial No. 257,326. (No model.)

To all whom it may concern:

Be it known that I, BUELL FRANK NEWCOMB, a citizen of the United States of America, residing at Watkins, in the county of Schuyler 5 and State of New York, have invented certain new and useful Improvements in Fences; and I do hereby declare the following to be a full, clear, and exact description of the invention, such as will enable others skilled in the art to 10 to which it appertains to make and use the same, reference being had to the accompanying drawings, and to letters or figures of reference marked thereon, which form a part of this specification.

15 My invention relates to certain new and useful improvements in fences; and it consists in the novel construction and arrangement of the parts thereof, as will be more fully hereinafter described, and pointed out in the claims.

20 One object of my invention is to sustain the fence-posts firmly above the surface of the ground upon a yielding base or support.

A further object of the invention is to provide the fence-panels intermediately between 25 the posts with a flexible binder or brace.

I attain these and minor objects by the construction illustrated in the accompanying drawings, wherein like letters of reference indicate similar parts in the several views, and in 30 which—

Figure 1 is a perspective view of a fence embodying my improvements. Fig. 2 is a side elevation, partly in section, of one of the fence-posts and its adjuncts.

35 A A indicate the posts, which, as shown, have suitable connecting-wires or runners, the upper runner passing through staples on one face or edge of the posts, and thence through a cross-cut in the top thereof down back to the rear side. The bottom of each of the posts A is seated upon a crucial supporting-base, and 40 is secured thereto by a pin or bolt inserted from the under side of said braces upwardly into the post, as fully shown in Fig. 2. Each

45 supporting-base consists of two boards, B, crossing each other centrally at right angles, said boards being of such thickness with relation to the weight of the fence as to yield slightly when the ends are supported above

ground, as shown. To the four faces of the 50 post, some distance above the base thereof, four anchor-wires, b, are secured and extend downwardly and outwardly to the outer ends of the cross-braces B, where they are secured to suitable staples, and then pass over the 55 outer ends of the braces, thence around a surface-block, C, of stone or other analogous material, and up through the braces, thence down around the outer edge of anchors D, arranged flush with the surface of the ground, thence 60 downward at an inward incline, as at b', and are secured to underground anchors b'', arranged at right angles to the direction of strain.

The four ends of the braces B rest upon surface anchors C, which are preferably of stone, 65 and are secured thereto. Directly under each anchor C underground anchors are situated. The said latter anchors, D, are of suitable dimensions and prevent the anchors C resting thereon sinking through the action of frost. 70 The inward portion of the wires b inclose both sets of anchors C and D, and prevent the same from becoming displaced outwardly from the ends of the cross-braces B. Each of the fence-posts is anchored in this manner, and between the posts a wire, d, is twisted around the runners, and is attached at its lower end to a wire, d', which in turn is secured to a single brace, E, which rests upon surface-anchors F, similar to the anchors C, heretofore described, 75 and the anchors F rest in turn upon underground anchors F'; similar to the anchors D. The ends of the wire are bent in such a manner as to inclose these anchors and extend inwardly, in the form as hereinbefore described. 80 Each panel of the fence will thus be anchored at the posts and intermediate thereof, as shown in Fig. 1. Owing to this arrangement the posts A can be positioned a greater distance apart, as the brace-wire D will support a part 85 of the lateral strain occasioned by wind or stock, thus effecting a material saving of lumber in sparsely-wooded sections of the country.

It is well known that aside from cost of construction one great point of advantage in wire 90 fences is that they will yield slightly to lateral pressure, and again assume a normal position when the pressure is removed. By my inven-

tion not only is this characteristic preserved, but increased, owing to the fact that the boards or strips of cross-brace B are capable of yielding to lateral pressure exerted on the post A, 5 as they are supported free from contact with the ground.

The arrangement of the anchors C and D affords great facility for straightening up the posts by tamping should they get out of plumb o from the action of frost or other causes.

What I claim is—

1. In a post-and-wire fence, the combination, substantially as described, of a post, a base consisting of spring-boards crossing each other centrally at right angles, anchors C and D beneath each end of the spring-boards to raise them free from the ground, and wires extending from the post around the anchors C and D, thence downward and inward to un-

derground anchors arranged at right angles to 20 the strain of the wire.

2. In a post and-wire fence, the combination, substantially as before set forth, of two or more posts supported above ground upon a yielding base consisting of cross-boards resting at their ends upon anchor-stones C and D, the brace-wires b b', arranged and secured as described, the fence-wires, and the flexible tie or brace d d', secured to the fence-wires and to an anchor-base at a point between two posts. 25 30

In testimony whereof I affix my signature in presence of two witnesses.

BUELL FRANK NEWCOMB.
